COMBINED SWITCH ACTUATOR AND FRAME

Charles D. Baxendell, Murraysville, Pa., assignor to The Bryant Electric Company, a corporation of Connecticut

Continuation of design applications Ser. No. 53,980, Dec. 30, 1958, and Ser. No. 53,981, Dec. 30, 1958.

This application Mar. 22, 1961, Ser. No. 64,429

Term of patent 14 years

(Cl. D26—13)

Fig. 1.

Fig. 2.

Fig. 3.

Fig. 4.

Fig. 5.

Fig. 6.

Fig. 7.

Fig. 8.

Fig. 9.

Fig. 10.

FIGURE 1 is a front view of a combined switch actuator and frame showing my new design, wherein the actuator is planar on its outer surface.

FIGURE 2 is a side view thereof.

FIGURE 3 is an end view thereof.

FIGURE 4 is a perspective view of the switch actuator and frame of FIG. 1, showing the actuator in one of two alternate positions.

FIGURE 5 is a perspective view of the switch actuator and frame of FIG. 1, showing the actuator in the other of the two alternate positions.

FIGURE 6 is a front view of the combined switch actuator and frame of my new design wherein the actuator is slightly depressed in the center along a horizontal line so as to be somewhat biplanar or rocker shaped..

FIGURE 7 is a side view of the switch actuator and frame of FIG. 6.

FIG. 8 is an end view of the switch actuator and frame of FIG. 6.

FIG. 9 is a perspective view of the switch actuator and frame of FIG. 6 showing the actuator in one of two alternate positions.

FIG. 10 is a perspective view of the switch actuator and frame of FIG. 6 showing the actuator in the other of the two alternate positions.

The characteristic features of the combined switch actuator and frame design are shown by solid lines.

This application forms a continuation of two of my earlier applications Serial Numbers D53,980 and D53,981, each having been filed December 30, 1958, entitled Wall Mounted Light Switch, and assigned to the present assignee.

I claim:

The ornamental design for a combined switch actuator and frame, substantially as shown and described.
